MACHINE FOR ASSEMBLING INSOLES AND
BACK PARTS OF SHOESRené E. Duplessis, Beverly, Mass., assignor to
United Shoe Machinery Corporation, Flemington, N. J., a corporation of New Jersey

Application June 6, 1941, Serial No. 396,900

15 Claims. (Cl. 12—1)

This invention relates to shoemaking machinery and is illustrated as embodied in a machine for use in assembling loose insoles and premolded back parts of shoes.

In the manufacture of open shank shoes, for example, it is common practice to build up separately the back parts of the uppers of the shoes and thereafter to mold them to their finished shape. Each of the premolded back parts is then positioned with relation to an insole secured to the bottom of a last and is thereafter permanently secured to the insole by fastenings which are arranged in the form of a letter U and are driven through a heel-seat flange of the back part and the margin of the heel portion 15 of the insole.

Improved methods of assembling premolded back parts and unattached insoles are disclosed in application for United States Letters Patent Serial No. 396,902, filed June 6, 1941, in my name. In practicing the method disclosed in said application Serial No. 396,902, the operator staples the forward ends of a heel-seat flange of the back part to opposite lateral margins of the insole while the ends of a U-shaped base crease, which is formed at the inside of the back part between the heel-seat flange and an upstanding portion of the back part, are forced against opposite lateral edges of the insole and while the heel portion of the insole is inclined lengthwise at a slight angle to a general plane in which the U-shaped base crease of the back part lies, the rear end of the insole at this time being spaced a substantial distance from the heel-seat flange and being in approximate engagement with the rear end of the inside face of the upstanding portion of the back part. The heel portion of the insole is then forced against the entire inside face of the heel-seat flange of the back part, causing the edge of the heel portion of the insole to be forced snugly against the entire base crease of the back part, with the result that an outer base or break line portion of the back part is conformed to the outline of the heel portion of the insole. While the insole 45 is thus forced against the heel-seat flange of the back part, a U-shaped line of tacks is driven through the heel-seat flange and the insole by a machine similar to that disclosed in application for United States Letters Patent Serial No. 396,901, filed June 6, 1941, in my name, in order permanently to secure the insole and the back part together.

To position insoles and back parts of shoes relatively to each other in the inclined relation 55

above described and to present them while so positioned to a fastening inserting machine, preparatory to securing the insoles permanently to the back parts by a U-shaped row of tacks, requires considerable time. Moreover, it has been found that when the assembling of the insole and the back part is left entirely to the judgment and skill of the operator, the edge of the heel portion of the insole is frequently not effectively forced, as desired, against the base crease of the back part during the subsequent operation in which the heel portion of the insole is forced against the inner face of the heel-seat flange of the back part.

With the above considerations in view, it is an object of the present invention to provide in a fastening inserting machine a device by the use of which premolded back parts and insoles of shoes may be assembled as well as presented quickly and accurately to fastening inserting mechanism of the machine.

With the above object in view and in accordance with a feature of the present invention, the illustrative machine comprises means for 25 relatively positioning a premolded back part and an insole of a shoe with the forward ends of an inside face of a heel-seat flange of the back part in engagement with the insole and the rear end of the insole in approximate engagement with an upstanding portion of the back part and spaced a substantial distance from the heel-seat flange of the back part, and fastening inserting mechanism, said means and said mechanism being mounted for relative movement to facilitate 30 the presentation of the forward ends of the heel-seat flange of the back part and adjacent portions of the insole to said mechanism.

The illustrative machine comprises a plate upon which the heel portion of an insole is positioned bottom up by a pair of abutments, and a pair of gages having edges which are arranged 40 substantial distances above and overlie the rear portion of the insole positioned upon the plate, said edges being shaped and arranged to be engaged by the rear portions of a base crease of a shoe back part, which is positioned upside down over the heel end of the insole, with the forward ends of its heel-seat flange in engagement with opposite lateral margins of the insole.

The insole supporting plate is pivoted at its forward end to a turret and is normally held against the upper face of the turret by a spring. The insole positioning abutments and the back part positioning gages are secured in predetermined positions to the turret, corresponding

abutments and gages being arranged in nested relation, each of the gages extending above and over a corresponding abutment. The turret is mounted for swinging movement upon a pedestal which is slidable from an operative position adjacent to fastening inserting mechanism to a work discharge position located some distance from said mechanism, the pedestal being normally held in its inoperative position against a stop by a spring.

After the insole and the premolded back part have been positioned as above described, the operator presses the opposite lateral wings of the back part toward each other, causing the opposite forward ends of the base crease of the back part to be forced against adjacent lateral edges of the insole, and then swings the turret, together with the work positioned thereon, until one forward end of the heel-seat flange of the back part is located below a fastening inserting nozzle and above a fastening clenching anvil of the machine. A fastening is then driven through the forward end of the heel-seat flange of the back part and through the insole to secure these parts together. The turret is then swung by the operator in an opposite direction to arrange the other forward end of the heel-seat flange of the back part positioned upon the insole beneath the nozzle, after which fastenings are driven through such forward end of the heel-seat flange and the insole.

In order to facilitate the removal of the assembled back part and insole from the machine, there is provided mechanism for swinging the work supporting plate into a raised position with reference to the turret so that the rear end of the plate will override the edges of the back part positioning gages when the pedestal is moved to its work discharge position.

By the use of the above device insoles and back parts of shoes can be quickly and effectively assembled in the above-mentioned relation preparatory to the subsequent permanent securing of these parts together by a U-shaped line of tacks driven through the heel-seat flange of the back part and through the insole.

The above and various other features of the invention will be understood and appreciated from the following detailed description read in connection with the accompanying drawings, in which

Fig. 1 is an angular view of an illustrative device for use in assembling insoles and premolded back parts of shoes;

Fig. 2 is an exploded view, partly broken away and partly in section, of a work supporting and assembling portion of said device;

Fig. 3 is a plan view, partly broken away, of the work support;

Fig. 4 is a perspective view of a premolded back part of a shoe;

Fig. 5 is an angular view showing the back part in the process of being assembled with an insole by the use of the device of Fig. 1;

Fig. 6 is a plan view, partly broken away, of the assembled insole and back part;

Fig. 7 is an angular view, partly broken away and partly in section, of the assembled back part and insole shown in Fig. 6;

Fig. 8 is an angular view showing the back part and the insole of Fig. 7 after they have been permanently secured together by a U-shaped line of tacks; and

Fig. 9 is a perspective view, partly broken away, of a finished shoe in which the assembled

back part and insole of Fig. 8 have been incorporated.

In practicing the method disclosed in the above-mentioned application Serial No. 396,902, 5 a premolded back part 20 which is to form part of an open shank shoe 22 (Fig. 9) is arranged upon an insole 24 in a predetermined position, which will appear later, and is attached thereto by staples 26 (Figs. 6, 7 and 8) or other suitable 10 fastenings which are driven through the heel end of the insole and the forward end portions of an inturned heel-seat flange 28 of the back part.

The illustrative back part 20 comprises a fiber counter 30 (Figs. 5, 7 and 8), a leather outer 32, 15 and a thin leather lining 34, said parts being assembled and sewed and/or cemented together while flat and afterwards being molded to the shape shown in Fig. 4, to provide the heel-seat flange 28 to which the insole is attached, and 20 an upstanding or heel band portion 36 which, in the finished shoe, encircles the heel of the wearer. The illustrative insole 24 comprises a fiber blank 38 to which is secured by cement 25 and/or staples a stiff fiber shank and heel piece 40, and a fabric or leather binding strip 42 which is wrapped about and is sewed to the edge portions of the blank and the shank and heel piece and the edge of which, as illustrated in Fig. 9, is exposed to view in the finished shoe 22.

For reasons explained in said application Serial No. 396,902, it is desirable to secure the back part 20 to the insole 24 by the staples 26 while the forward ends of a crease 44, which is formed between the upstanding portion 36 and the heel-seat flange 28 of the back part and may be referred to as a base crease, are forced against the opposite lateral edges of the insole, as illustrated in Fig. 5, and a planar heel portion 46 of the insole is inclined at a slight angle to a general plane in which the heel-seat flange 28 and the U-shaped base crease 44 lie, the rear end of the insole 24 being spaced a substantial distance from the heel-seat flange, as indicated by reference numeral 48 (Figs. 5 and 7), and being in approximate engagement with a rear portion 48 (Figs. 5, 7 and 8) of the inside surface of the upstanding portion 36 of the back part. During this stage of the assembly of the back part 20 and the insole 24, the rear end of the insole is usually in engagement with the inside face of the upstanding portion 36 of the back part and the term "approximate engagement" is intended to include this arrangement.

It is highly desirable for reasons set forth in said application Serial No. 396,902, that in the finished shoe the entire base crease 44 of the back part 20 shall be in snug engagement with an edge 50 of the heel portion 46 of the insole of the shoe. It is common practice to incorporate premolded back parts 20 of the same size and shape in shoes of slightly different sizes and/or styles. Since the heel portions 46 of insoles 24 of shoes vary in size and shape in accordance with the sizes and styles of the shoes, it will be appreciated that in order to cause the base crease 44 of the back part to be brought into snug engagement with the edge 50 of the heel portion 46 of the insole 24 preparatory to securing the insole permanently to the back part, a base rim portion of the back part (that is, a portion of the back part in the vicinity of a break line 51, Figs. 5, 7 and 8, of the back part) usually has to be flexed to a considerable extent. In practicing the method disclosed in said application Serial No.

396,902, the operator, after securing the back part 20 to the insole 24, as above described and as illustrated in Fig. 7, by the use of staples 26, causes, by the use of a modified heel-seat lasting machine such as disclosed in said application Serial No. 396,901, the margin of the heel portion 46 of the insole 24 to be forced with considerable pressure against an inner face 52 (Fig. 4) of the heel-seat flange 28 of the back part, the entire base crease 44 of the back part being forced into snug engagement with the edge 50 of the heel portion 46 of the insole and being conformed to an outline similar to that of such edge. The base rim portion of the back part 20 may thus be described as being conformed during the above operation to an outline similar to that of the edge 50 of the heel portion 46 of the insole, the break line 51 being substantially continuous with the lateral edges of the shank portion of the insole and merging gracefully therewith. While the insole 24 and the heel-seat flange of the back part 20 are thus forced or clamped together, a plurality of tacks 56 (Fig. 8) arranged in the form of a letter U are driven through the heel-seat flange of the back part and the heel portion of the insole in order permanently to secure together the back part and the insole. By practicing the above method, back parts 20 may be assembled with and permanently secured to insoles 24 quicker and more accurately than has heretofore been possible.

In order to position the back part 20 with reference to the insole 24, as above described, preparatory to stapling together the back part and the insole, there is provided a work support or device 58 (Fig. 1) which comprises a pedestal 60 a base portion 62 of which fits in a guideway 64 of a supporting bracket 66 fixed to a main frame of a staple driving machine such, for example, as disclosed in United States Letters Patent No. 1,557,561, granted October 20, 1925, on an application filed in the name of John W. Cosgrove, the arrangement being such that the pedestal may be moved from an operative position (shown in full lines in Fig. 1), in which it is in engagement with a stop face 68 and is located adjacent to a nozzle 70 of a staple driving unit (not shown) and adjacent to a fastening clenching anvil 72 secured by screws 74 to the bracket 66, to an unloading position (shown by dash lines in Fig. 1).

Mounted upon the pedestal 60 is a turret 76 (Figs. 1, 2 and 3) having a depending shank 78 (Fig. 2) shaped and arranged to fit in a recess 80 formed in the upper end of the pedestal. The turret 76 is held against upward displacement upon the pedestal 60 by a retaining pin 82 which is secured to the pedestal and fits in a circular channel 84 in the depending shank 78. Formed in the shank 78 of the turret 76 is a vertical slot 86 which is wider than the diameter of the retaining pin 82, the arrangement being such that the turret may be quickly removed from the pedestal 60 by rotating the turret 180° about an axis 87 of the shank 78 from its operative position shown in Fig. 1, and then lifting the turret from the pedestal.

Mounted upon the turret 76 is a sole supporting plate 88 having at its rear end notches 90 (Figs. 1, 2 and 3) and at its forward end a depending apron 92 (Fig. 2) which is pivoted upon a fulcrum pin 94 secured to the turret. Fitting in a Y-shaped groove 96 (Fig. 3) in the upper face of the turret 76 and riveted to said turret is a gage 98 having a pair of upstanding abut-

ments or lugs 100 which extend through the notches 90 of the plate 88 and are shaped and arranged to be engaged by the rear end of the insole 24 and to position the insole lengthwise and widthwise upon the plate. Formed integral with the gage 98 is a flexible flange 102 (Fig. 2) which is constantly forced against the apron 92 of the plate 88, the arrangement being such that the plate is normally held in engagement with an upper surface 104 (Figs. 1 and 3) of the turret 76 but may be swung in a clockwise direction, as viewed in Fig. 1, about the pivot pin 94, by mechanism which will appear later, to facilitate the removal of the work from the machine.

Arranged between an upper surface 106 (Fig. 2) of the pedestal 60 and the bottom of a shallow depression 108 in the bottom of the turret 76 is a gage 110 having an upstanding block 112 (Figs. 1, 2 and 3) which fits in an elongated guideway 114 of the turret and into which is threaded an adjusting screw 116. The end of the screw 116 is normally forced against an end face 118 (Figs. 1 and 3) of the guideway 114 through the provision of a spring 120 (Fig. 2) which is arranged in a recess 122 of the turret and has its opposite ends in engagement with the turret and an upstanding flange 124 at the forward end of the gage 110. Formed in the gage 110 is an elongated slot 126 through which passes the shank 78 of the turret 76, said gage having at its rear end a pair of upstanding abutments or lugs 128 the upper edges 130 of which are usually arranged just above and slightly forward of corresponding abutments 100 and are shaped and arranged to be engaged by the rear portions of the base crease 44 of the back part 20 in order to facilitate the positioning of the back part upon the insole 24, as illustrated in Fig. 5. The abutments 128 may be initially moved into different operative positions lengthwise of the insole by turning the screw 116.

The turret 76 is normally held in its neutral position, shown in Fig. 1, in which a central plane 132 of the turret is arranged approximately parallel to the guideway 64 of the bracket 66, by a spring 134 the upper and lower ends of which are secured to the turret and to an extension 136 of the pedestal. The pedestal 60 is constantly urged to its operative position (shown in full lines in Fig. 1) against the stop face 68 by a spring 138 opposite ends of which are connected to the bracket 66 and the pedestal 60, the sole supporting plate 88 at this time being arranged adjacent to the fastening inserting nozzle 70 and to the fastening clenching anvil 72.

In assembling the premolded back part 20 and the loose insole 24, the operator places the heel portion 46 of the insole bottom up on the plate 88 with the rear end of the insole in engagement with the abutments 100 and then positions the back part over the heel end of the insole, as illustrated in Fig. 5, with the rear portion of the base crease 44 of the back part in engagement with the upper edges 130 of the abutments 128, the forward ends of the base crease being moved into engagement with the opposite lateral edges of the insole by the operator. Should one lateral portion or wing of the back part 20 project forwardly of the other, the back part is shifted by the operator to a slight extent circumferentially of the heel part of the insole until the forward ends of the heel-seat flange 28 are arranged opposite each other. When the insole 24 and the back part 20 are thus positioned upon the support, the general plane of the heel portion 46 of

the insole is inclined lengthwise to the general plane which includes the base crease 44, the rear end of the insole being spaced rearwardly of and a substantial distance from the heel-seat flange 28 and being in approximate engagement with the rear inside face 48 of the upstanding portion 36 of the back part. The operator then swings the turret 76, together with the work mounted thereon, in one direction about the axis 87 (Fig. 2) to move one of the forward ends of the heel-seat flange 28 directly beneath the fastening inserting nozzle 70 and over the clenching anvil 72. A treadle (not shown) is then depressed, causing fastening inserting mechanism (not shown) to be operated, thereby driving one or more staples through the heel-seat flange 28 of the back part 20 and through the heel portion of the insole 24. The turret 76 and the work mounted thereon are then swung in an opposite direction about the axis 87 to move the opposite end of the heel-seat flange 28 to a position beneath the fastening inserting nozzle 70 and over the anvil 72 preparatory to driving staples 26 through the opposite end of the heel-seat flange and the insole.

After the insole 24 and the back part 20 have been stapled together as shown in Fig. 7, it will be appreciated that the rear end of the insole is spaced a substantial distance from the end of the heel-seat flange 28 of the back part. Moreover, the edges 130 of the abutments 128 overlie and extend slightly forward of the rear portions of the insole 24. Accordingly, it is desirable, preparatory to removing the assembled insole and back part from the machine, to swing or tilt the plate 88 in a clockwise direction, as viewed in Fig. 1, about the fulcrum pin 94 (Fig. 2) until the rear end of the plate, together with the rear end of the insole mounted thereon, is raised slightly above the upper edges 130 of the abutments 128, thereby enabling the operator to slide the assembled insole and back part rearwardly from the plate.

In order to tilt the plate 88 upwardly as above described, there is provided a rod 140 which is guided for movement in a cylindrical recess 142 of the pedestal 60. The upper end portion of the rod 140 passes through a recess 144 in the shank portion 78 of the turret 76 and, when the pedestal 60 is in its operative position, is arranged just below the bottom face of the plate 88. In order to raise the rod 140 and therefore to swing the plate 88 in a clockwise direction (Fig. 1) as the pedestal is moved to the left from its full line position adjacent to the fastening inserting nozzle 70, there is provided a bifurcated lever 146 the forward end of which is pivoted upon a fulcrum pin 148 carried by the base portion 62 of the pedestal 60. Arms of the bifurcated lever 146 are provided with faces 150 which are constantly engaged by a pin 152 secured to the rod 140 and extending through elongated slots 154 formed in the opposite sides of the pedestal 60. Mounted upon the arms of the bifurcated lever 146 are rolls 156, the arrangement being such that when the pedestal is moved to the left, as viewed in Fig. 1, along the guideway 64, the rolls 156 slide up inclined ramps or cams 158 of the bracket 66, causing the rod 140 to be raised and the plate 88 to be swung to its dash line position shown in Fig. 1. With such an arrangement the operator, after assembling the insole 24 and the back part 20, slides the pedestal to the left along the guideway 64 to move the heel end of the assembled insole and back

part from beneath the nozzle 70. The work is then slid heel end first from the work support, which is then released and under the action of the spring 138 returns to its operative position.

In order to vary the distance between the rear end portions of the plate 88 and the upper edges 130 of the abutments 128 in accordance with the thickness of the insole and the desired angle between the plane of the heel portion 48 of the insole and the general plane of the base crease 44, the initial operative position of the plate 88 may be varied through the provision of a screw 160 which is threaded into one of the arms of the bifurcated lever 146 and the lower end of which engages the bracket 66.

Having described my invention, what I claim as new and desire to secure by Letters Patent of the United States is:

1. A machine for use in assembling insoles and back parts of shoes having, in combination, means to facilitate the relative positioning of a premolded back part and an insole of a shoe with the forward ends of a base crease, which is formed in the back part between a heel-seat flange and an upstanding portion of the back part, in engagement with opposite lateral edges of the insole and with the remaining portions of the base crease spaced from the insole, and fastening inserting mechanism, said means and said mechanism being mounted for relative movement to facilitate the presentation of the forward ends of the heel-seat flange of the back part and adjacent portions of the insole to said mechanism preparatory to driving fastenings through the insole and the forward ends of the heel-seat flange.

2. A machine for use in assembling insoles and back parts of shoes having, in combination, means for relatively positioning a premolded back part and an insole of a shoe with the forward ends of an inside face of a heel-seat flange of the back part in engagement with the insole and the rear end of the insole in approximate engagement with an upstanding portion of the back part and spaced a substantial distance from the heel-seat flange of the back part, and fastening inserting mechanism, said means being movable to transfer the insole and the forward ends of the heel-seat flange of the back part positioned thereon to positions adjacent to said mechanism preparatory to driving fastenings through the forward ends of the heel-seat flange and the insole.

3. A machine for use in assembling insoles and back parts of shoes having, in combination, means comprising a plate for relatively positioning a premolded back part and a loose insole of a shoe with the forward ends of an inside face of a heel-seat flange of the back part in engagement with portions of the insole and with the remaining portion of said face spaced from the insole and the rear end of the insole in approximate engagement with an upstanding portion of the back part, said plate being shaped and arranged to enable the operator to force against opposite lateral margins of the insole the forward ends of a base crease formed in the back part between the heel-seat flange and an upstanding portion of the back part, and fastening inserting mechanism, said means being mounted for movement to transfer the insole and the forward ends of the heel-seat flange of the back part in engagement with the insole to positions adjacent to said mechanism preparatory to driv-

ing fastenings through the forward ends of the heel-seat flange and through the insole.

4. A machine for use in assembling insoles and back parts of shoes having, in combination, a support for the heel portion of an insole, means for positioning said heel portion of the insole upon the support, gages for positioning a premolded back part of a shoe relatively to said insole with the rear portion of a heel-seat flange of the back part spaced a substantial distance from the rear part of the heel portion of the insole and with the forward portions of said heel-seat flange in engagement with opposite lateral margins of the insole upon said support, and means for securing together the forward end portions of the heel-seat flange of the back part and the insole.

5. A machine for use in assembling insoles and back parts of shoes having, in combination, a support for the heel portion of an insole, means for positioning the insole upon the support, gages for positioning a premolded back part of a shoe relatively to said insole with the forward portions of a heel-seat flange of the back part in engagement with opposite lateral margins of the insole and with the remaining portion of said heel-seat flange spaced from the heel portion of the insole, and fastening inserting mechanism, said support, said insole positioning means and said gages being mounted for movement as a unit to facilitate the presentation of said relatively positioned insole and back part to said mechanism preparatory to driving fastenings through the forward end portions of the heel-seat flange of said back part and through the insole.

6. A machine for use in assembling insoles and back parts of shoes having, in combination, a support for the heel portion of an insole, gages normally projecting above the support for positioning an insole and a premolded back part of a shoe in predetermined positions upon the support, and means for securing the insole to the forward portions of a heel-seat flange of the back part, said support being movable to a raised position with relation to said gages to facilitate the removal of the secured-together insole and back part from the support.

7. A machine for use in assembling insoles and back parts of shoes having, in combination, means for positioning the heel portion of a loose insole, means for positioning with relation to the heel portion of the insole a shoe back part with a heel-seat flange thereof disposed approximately in a plane inclined at a slight angle to a general plane of the heel portion of the insole, and fastening inserting mechanism, said means being movable with relation to the fastening inserting mechanism to transfer successively the forward ends of the heel-seat flange of the back part and opposed portions of the insole to positions adjacent to said mechanism preparatory to inserting fastenings through the forward end of said heel-seat flange and through the insole.

8. A machine for use in assembling insoles and back parts of shoes having, in combination, means for positioning a heel portion of an insole, means for positioning a premolded shoe back part with reference to the insole with the forward ends of the heel-seat flange of the back part in engagement with opposite lateral margins of the insole and with the rear portion of said heel-seat flange spaced a substantial distance from the heel end portion of the insole, and means for inserting fastenings through the forward ends of the heel-seat flange of the back part and

through the insole to secure the back part and the insole together.

9. A machine for use in assembling insoles and back parts of shoes having, in combination, 5 a support for an insole of a shoe, gages constructed and arranged to be engaged by the rear end of the insole to position the same upon the support, gages constructed and arranged to be engaged by the rear end portion of a base crease, 10 which is formed at the inside of a shoe back part between a heel-seat flange and an upstanding portion of the back part, to position said back part with the forward ends of its heel-seat flange in engagement with the insole and with the remaining portion of its heel-seat flange spaced 15 a substantial distance from and inclined lengthwise to the heel portion of the insole, and fastening inserting mechanism, said gages and said support being mounted for pivotal movement to enable the operator to swing the forward end portions of the heel-seat flange of the back part together with the adjacent portions of the insole successively to positions adjacent to said fastening inserting means preparatory to driving fastenings 20 through the forward end portions of said flange and through the insole.

10. A machine for use in assembling insoles and back parts of shoes having, in combination, a plate having a face, said face being constructed 25 and arranged to support the heel portion of an insole but to insure that the forward lateral margins of the heel portion shall extend beyond adjacent lateral margins of the plate, gages for locating the heel portion of the insole upon the 30 plate, gages extending above the rear portion of the face of said plate and constructed and arranged to engage the rear portion of a base crease of a premolded shoe back part, which crease lies approximately in a plane and is formed 35 between a heel-seat flange and an upstanding portion of the back part, the arrangement being such that the forward ends of the crease may be forced by the operator against opposite lateral edges of the insole and the general plane of the 40 crease is inclined at a slight angle to a general plane of the heel portion of the insole, and means for inserting fastenings through the insole and through the forward ends of the heel-seat flange of the back part.

11. A machine for use in assembling insoles and back parts of shoes having, in combination, 45 a turret, a plate supported by the turret, gages extending above the plate and constructed and arranged to position the heel portion of an insole upon the plate, gages for positioning a premolded shoe back part upon the insole, said second-named 50 gages extending above and slightly forward of the insole positioning gages, fastening inserting mechanism, said turret and plate being movable to enable the operator to transfer the insole and the back part positioned upon the plate to desired positions adjacent to said fastening inserting mechanism preparatory to driving fastenings through the insole and through a heel-seat flange of the back part, resilient means for constantly moving the turret to an operative position, and means associated with the turret for raising the plate with relation to the gages when the turret is moved away from its operative position.

12. In a machine for assembling insoles and back parts of shoes, a support for the heel portion of an insole, means for positioning the heel portion of the insole upon the support, means projecting above the support for locating a pre-

molded shoe back part with relation to the insole upon the support, means for inserting fastenings through the insole and through the back part to secure the same together, said support being movable to and from an operative position adjacent to the fastening inserting means, and means responsive to movement of the support away from said fastening inserting means, for moving the support to a predetermined position with relation to said insole and back part positioning means to facilitate removal of the secured-together insole and back part from the machine.

13. In a machine for assembling insoles and back parts of shoes, fastening inserting mechanism, a stop, a pedestal movable to and from an operative position which is determined by the stop and is located adjacent to said mechanism, resilient means for normally retaining the pedestal in its operative position, a turret mounted upon the pedestal, a plate mounted upon the turret, gages which are stationary with relation to the turret and which extend above the plate and are constructed and arranged in combination with the plate to locate a shoe back part and a loose insole of a shoe with relation to each other, said turret and said plate being mounted for swinging movement with relation to the pedestal to present portions of the insole and the back part to the fastening inserting mechanism preparatory to securing these parts together, and means responsive to movement of the pedestal away from said fastening inserting mechanism for moving the plate to a predetermined position with relation to the tur- 35

ret and the gages to facilitate the removal of the assembled insole and back part from the machine.

14. In a machine for assembling insoles and premolded back parts of shoes, fastening inserting mechanism, a support for the heel end portion of an insole, gages for positioning the heel end portion of the insole upon the support, abutments for locating a premolded shoe back part in a predetermined position upon the insole, said support, said gages and said abutments being mounted for pivotal movement as a unit with relation to said mechanism preparatory to driving fastenings through the insole and through the forward ends of a heel-seat flange of the back part, said support, said gages and said abutments being mounted for translatory movement away from said mechanism, and means for effecting relative movement of the support on the one hand and the abutments and the gages on the other hand during said translatory movement away from the fastening inserting mechanism to facilitate the removal of the assembled insole and back part from the machine.

15. In a machine for assembling insoles and back parts of shoes, a turret, a work support, gages secured to the turret, said gages being constructed and arranged to locate an insole and a premolded back part of a shoe upon the support, fastening inserting mechanism, said support, said gages and said turret being mounted for pivotal movement together, and means for moving the support with relation to the gages and the turret.
